UNITED STATES PATENT OFFICE.

FRANCIS KOENIG, OF PHILADELPHIA, PENNSYLVANIA, ASSIGNOR TO
REINHOLD G. LEDIG, OF SAME PLACE.

DESIGN FOR A TABLE.

SPECIFICATION forming part of Design No. 22,015, dated November 22, 1892.

Application filed October 19, 1892. Serial No. 449,400. Term of patent 3½ years.

To all whom it may concern:

Be it known that I, FRANCIS KOENIG, a subject of the Emperor of Germany, (having resided one year last past in the United States 5 and declared my intention of becoming a citizen thereof,) residing in the city and county of Philadelphia, State of Pennsylvania, have invented and produced a new and original Design for a Table, of which the following is 10 a specification, reference being had to the accompanying drawing, forming part thereof.

The leading features of my design for a table are the ornamental top frame, ornamental legs with outwardly-bowed upper ends, 15 and a lower shelf with the legs passing through the same.

In the drawing, A designates the top frame of the table, the same having ornamental sides B, the center of said latter depending 20 as at C.

D designates the legs, which are bowed outwardly at top, as at E, the portions having scrolls F, which narrow downwardly. The portion of the legs below said scrolls bow inwardly, as at G.

H designates the lower shelf, the same having an ornamental border J, at the corners of which are bosses K, through which pass the legs D. The top L has bulges M at the corners thereof.

What I claim is—

The design for a table, substantially as shown and described.

FRANCIS KOENIG.
